FILLING MACHINE

Frank J. Cozzoli, Plainfield, N. J.

Application February 19, 1946, Serial No. 648,723

12 Claims. (Cl. 103—38)

1

The present invention relates to dispensing machines adapted for the filling of ampoules, vials, tubes and like containers with measured amounts of pharmaceutical preparations. The invention aims primarily, to render available a dispensing machine capable of dispensing variable but an accurately measured quantity of a preparation into a container in a manner such that splashing and consequent wetting of the throat or neck of the container is avoided.

Another aim of the invention is to render available a variable but positive displacement dispensing machine incorporating a stroke adjusting arrangement whereby and wherewith a precisely measured charge entrained in the measuring cylinder on an intake stroke is substantially completely discharged therefrom on completion of the delivery stroke under any quantity setting within the range of the machine.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is a front view of a filling machine illustrating a typical use and embodiment of the invention.

Fig. 2 is a side view of the machine, partly in section taken substantially along line 2—2 of Fig. 1.

Fig. 3 is a detail plan view of a portion of a stroke varying and locking device.

Fig. 4 is an enlarged view of a preferred form of slide actuating means constructed in accordance with this invention.

Figs. 5 and 6 are respectively front and side views of portions of variant form of variable stroke follower actuating means.

Fig. 7 is a front view of another form of actuator.

Referring more particularly to Figs. 1 and 2 of the drawings the invention is disclosed in combination with a filling machine wherein it performs an especially advantageous function. As will later become apparent other uses of the invention are contemplated and the reference to a filling machine is for explanatory purposes. The filling machine disclosed has a main supporting base 10, to which a hollow front panel member 11 is firmly secured by screws or other conventional means. Atop the panel 11, a unit

5 base plate 12 is bolted and which projects forward to form a support for one or more filling units, indicated generally at 13. The plate 12 in turn supports a slides panel 14 which is closed at its top by a cap member 15, and at its rear in part by a plate 16 and in part by a housing 17 that also encloses the main drive means.

10 Each filling unit 13 comprises essentially a body member 18 having aligned bores to receive respectively a measuring cylinder and piston 19 and 20, and a drop eliminator cylinder and piston 21 and 22. A liquid intake port 23 communicates with the lower end of the measuring cylinder 19, and in which a one-way valve, preferably 15 a ball valve 24, is located. On the piston side of the valve 24, a fluid connection 25 is made with the drop eliminator cylinder 21 which is also provided with a ball check valve 26 at its lower end. On the piston side of the valve 26 a 20 fluid connection 27 is made with an ampule filling needle 28. The needle 28 is hollow, as is the connection 27, and is adapted to conduct the liquid preparation into the ampule which is held on telescoped relation therewith during the filling operation. On an upstroke of the measuring piston 20, liquid enters the cylinder 19 past the valve 24, and on a down stroke of the piston the liquid is discharged through the port 25, past 25 valve 26 into cylinder 21, and out through the nipple 27 and filling needle 28. The ball valves 24 and 26 alternately open and close during a filling cycle, as will be understood. The unit body 18 is provided with lateral flanges 29 which are fitted to corresponding recesses in the plate 30 35 12 and is held in place by holding screws 30.

In the Fig. 2 position of the pistons of the filling unit, the piston 20 of the measuring cylinder is at its lowest extreme position, and piston 22 of the drop eliminator cylinder at its lowest 40 position wherein its upper end is a short distance away from the underside of the cylinder cap 31. In this position the discharge stroke is completed. When the pressure exerted upon the upper end of the piston 22 is removed, a compression spring 32, acting between the cylinder cap 31 and a washer 33 secured to the upper end of the plunger 22, operates to retract the piston 22 a limited distance. Pressure on the upper end of the drop eliminator plunger is relieved 45 at the beginning of the intake stroke of the measuring piston, and the resulting lifting of the piston 22, causes a portion of the fluid entrained in the filling needle 28 and conduit 27 to return to the cylinder 21. Any droplet of liquid 50 that tends to adhere to the end of the needle

is caused, by the action above explained, to be drawn into the needle where it is more or less enclosed and prevented from falling off or from becoming fouled or contaminated.

Reciprocating motion is imparted to the measuring piston 20, in accordance with this invention, by a two-part slide member 35, 36, and a slide actuator. The upper section 35 of the slide is yieldingly connected to the lower section 36, by a stud 37 and a jam nut 38. The sections are spring urged apart a predetermined distance by a preloaded compression spring 39 that encircles the stud 37 and is seated in recesses 40 in the adjacent ends of the slide blocks 35 and 36. The two blocks are by this arrangement caused to move normally in unison within guides 41 and 41b provided in the upper panel 14 and in the lower panel 11 respectively.

The slide block 35 connects directly with the piston 20 by means of a short stud 42 driven into the block 35 and which has its outer end reduced to enter a hole 43 formed in the upper end of the piston extension. The block 35 also carries a second and similar bar 44 that extends over the end of piston 20 and carries at its end an adjustable screw 45. The screw 45 is adjusted to engage with and actuate the drop eliminator piston 22 a limited distance during the final portion of the discharge stroke of the measuring piston. Aligned with the piston rod of the measuring piston is a button 46 mounted in the presser bar 44, which is fitted closely to the top of the piston rod so that there is no appreciable looseness between that piston and its actuating pin 42, but which allows the filling unit as a whole to be readily removed from the machine upon removal of the holding screws 30. The guide ways 41 in the panels 11 and 14 are rectangular in cross section, corresponding to the shape of the slide block 35, 36, and are closed at the rear side by a plate 41a.

The lower end of the slide block projects through an opening provided in the unit base 12 and into the interior of the lower panel 11, and has secured thereto an antifriction roller 50. Underlying the roller 50 and normally engaged thereby is an actuating cam lever 51 which has, preferably a curved roller engaging contour. The cam 51 is according to this invention oscillatable and bodily rotatable, its oscillatory movement being fixed as to amount in all of its rotationally adjusted positions. As illustrated more clearly in Figs. 1 and 4, the cam lever 51 is pivoted, as at 52, to a revolvable support 53. The support 53 is journaled about a drive shaft 54 that carries a crank member 55 at its outer end. The crank pin end 56 of the crank connects with the cam lever 51 by means of a connecting rod 57. Anti-friction bearings 58 fitted to the connecting rod eyes 59 and centered on screws 60, are provided to establish a secure but frictionless drive connection between the crank and cam lever.

Rotary motion is imparted to the crank by a motor 61 operating through a belt 62 and a variable speed pulley 63 mounted upon the worm shaft 64 of a speed reducing unit 65. The worm wheel 66 of the reducer is secured to the crank shaft 54. The variable speed drive 63 is of conventional design consisting of a pair of axially movable sheaves 63a that are normally spring pressed toward each other but which spread, when the pulley center distances are moved apart, to allow the belt to run on a smaller pitch diameter. In this instance the motor 61 is moved to change the center distance, as by tilting the motor base 67 about its pivot 68 by operating an adjusting screw 75

knob 69. The knob 69 operates on a screw stud 70 carried by the reducing unit and engages a depending portion 71 of the motor base 67.

When the motor is energized the crank shaft 54 and crank 55 are caused to revolve and effect oscillation of the cam lever 51 about its pivot 52. A preferred proportioning of the elements is illustrated in Fig. 4 wherein the crank is on dead center and the connecting rod 57 extends substantially vertically and engages the cam lever approximately 60° away from its fulcrum point 52, using the center of the crank shaft 54 as the point of measurement. As the crank 55 revolves, the connecting rod 57 swings the cam lever 51 about its pivot 52 until the position represented by the dotted lines b is reached. During the movement, the slide roller 50 rolls outwardly on the periphery of the cam and simultaneously is lifted thereby to the position shown by the dotted lines in Fig. 4. Further turning of the crank, lowers the cam lever to the full line position shown, and the slide and roller 50 follow down with it. In this particular instance the roller slide is made to have substantial mass, and means other than the force of gravity, is not required to effect a lowering of the slide and its connected piston. Where, however, mass alone is not to be relied upon, the cam lever 51 may be grooved to receive the follower roller, or otherwise constructed, to effect positive movement of the slide in each direction, as illustrated, for example, in Fig. 7.

Normally the cam lever supporting bracket 53 is locked in a set angular position, and when stationed in the full line position shown by Fig. 4, the slide reciprocations resulting are at the maximum. However, if the bracket 53, is rotated clockwise to a station that places the pivot 52 coincident with the axis of the follower roller 50, the lever 51 is caused to oscillate from position c to d which is the same range as before, but the extent of slide reciprocations resulting is zero because the fulcrum 52 of the lever coincides with the axis of the slide roller and the face of the cam 51 follows the periphery of the follower 50.

In the present embodiment of the invention, in a sensitive filling machine, it is important that the measuring piston travels down to a definite position at every volume setting, from zero delivery up, and to insure the stopping of the piston travel at a definite point, a stopping abutment 80 is provided. The abutment is located in the lower end of a slot 81 formed in the panel 14 through which the piston actuator bars 42 and 44 extend and is of such effective height as positively to stop the downward travel of the piston and piston actuating slide at a definite point. Ordinarily the point of stopping will be set to bring the lower end of the piston approximately even with the top of the duct 25 in the filling body to insure against air or gas entrapment, and the roller slide correspondingly adjusted, via the nut and stud 38, 37, to bring the roller 50 into contact with the cam 51, when the latter is in its lowest position. Preferably the follower engaging surface of the cam 51 is a portion of a circle which has its center coincident with the center of rotation of the supporting arm of the movable bracket 53, when the cam lever is at its lowest (or innermost) position at which point, the axis of the follower roller is coincident with the pitch circle p of the pivoted lever.

It will be evident from the foregoing that in adjusting the cam lever 51 angularly relative to the line of movement of the slide 36 and its roller 50, the effective stroke of the slide is varied from

zero to maximum with the variations occurring at the upward end of the stroke only. The lower end of the stroke being determined in each instance by the cam lever 51 reaching its concentric position.

As illustrated in Fig. 4, the oscillations of the cam lever occur, with the parts arranged as shown, outside of the circle inscribed by the lever 51 when it is in its extreme retracted position and the change in stroke length of the follower occurs at the outer (or upper) end only. The relation of parts may, however, be reversed merely by substituting a shorter connecting rod for the rod 57 and whereby the oscillations can be caused to occur wholly within the said circle. Figs. 5 and 6 illustrate an arrangement of parts designed to effectuate that action. In these figures the elements that correspond to those previously described are numbered 150, 151, etc., and the oscillatable lever 151 is shown in full lines in its maximum throw position wherein its periphery, if projected, inscribes a circle. As the crank 155 revolves, from the position illustrated, the lever 151 is rocked inwardly to the dotted line position *bb*, and the follower roller 150 follows down with it. If the pivot point 152 of the lever is rotated clockwise 60°, the lever oscillations are the same magnitude as before, but the follower roller 150 engages the circular hub end 151a of the lever and its reciprocations are zero. Between the extremes mentioned, any angular adjustment of the pivot 152 effects a proportionate change occurring at the lower end of the stroke, the upper limit of the stroke remaining constant. A mechanical movement of this character, i. e., with its stroke change at the lower end of the follower movement, is adaptable to inverted piston and cylinder pump devices of the type disclosed in my prior application Ser. #594,462, filed May 18, 1945.

Referring more particularly to Figs. 1 and 3, a form of stroke adjusting means is illustrated which comprises a lever 85 that is secured to the adjustable support 53. The free end of the lever extends through a slot 87 in the cover 17 and is provided with a pull pin type of handle 88. The handle 88 is threaded to one end of a slotted draw bolt 89, the slot in which receives the peripheral portion 90 of an arcuate flange 91 secured to the panels 11 and 14. When the handle 88 is tightened the bifurcated end of the draw bolt draws the lever 85 and flange 91 tightly together and angular movement of the lever and the bracket 53 secured thereto is prevented.

The projecting end of the lever 85 is adapted to sweep across the flange 91 in moving the bracket 53 from zero displacement to maximum displacement position. The flange may be appropriately calibrated as at 92, to indicate the major divisions of stroke changes. Preferably end stop pins 93 are positioned in the flange 91 to limit the extremes of movement of the stroke adjusting lever 85. A shifting of the adjusting lever 85 effects an angular readjustment of the bracket 53 and the pivot of the slide actuating lever 51, and a corresponding change in the stroke of the slide 36.

Precision regulation of the stroke of the piston 20 of the measuring cylinder is had by controlling its upper extreme stopping position independently of the stroke of the actuating slide. To effect that result an adjustable but normally stationary and positive abutment is provided in the form of a micrometer stop device 95. The micrometer stop comprises an interiorly threaded barrel 96

that is firmly clamped to the cap member 15 in axial alignment with the measuring cylinder, a cooperating threaded spindle 97, and an adjusting sleeve 98 that is suitably fastened to the spindle.

5 The micrometer sleeve and barrel are graduated as at 98 to indicate unit and fractional units of displacement with a high degree of accuracy.

The lower end of the micrometer spindle 97 projects from the micrometer barrel and forms 10 an anvil against which the cross-bar 44 stops when elevated. The stopping of the cross-bar 44 also, by reason of the button 46, positively stops upward movement of the measuring piston at the precise point desired. Assuming, that 15 the follower 50 and slide 36 has not completed its upward stroke by the time the micrometer abutment limits further piston travel, the spring 39 between the blocks 35 and 36, will be compressed the necessary amount. Preferably, the follower 20 slide stroke and piston stroke will be such that the follower slide 36 has a slight excess or overtravel to insure the bringing of the piston against its positive stop 97 before the actuating slide 36 reaches the upper end of its travel.

25 To avoid conflict between the setting of the micrometer stop and the stroke of the piston actuating slide, an interlock mechanism between the micrometer and the stroke adjusting lever is provided. As illustrated more clearly in Figs. 1

30 and 2, the interlock includes a stop shoe 100 that partially encircles the micrometer barrel 98 and underlies an annular rim or flange 101 formed thereon. The stop shoe is mounted upon the upper end of a vertically shiftable rod 102. The 35 rod 102 is slidable in bearings provided in and by the cap and panel members 15 and 14 and extends downwardly into the lower panel member 11. At its lower end, the rod carries a roller 103 which engages a cam surface 104 formed upon an

40 extending arm 105 of the bracket 53. Angular movement of the cam carrying bracket 53 via lever 85, likewise effects angular movement of the arm 105 and vertical movement of the roller 103, rod 102, and stop shoe 100.

45 In the arrangement disclosed the contour of the interlock cam 104 is plotted not only to utilize the bodily movement of the arm 105 in moving from its horizontal position shown in dotted lines in Fig. 4 to its full line position but to effect a uniform lift of the roller 103 for each angularly adjusted position 50 of the lever 51 whose increments of angular movement are not uniform. With an interlock so arranged it becomes impossible to adjust the micrometer stop downwardly (to shorten the stroke

55 and delivery capacity of the filling unit) without first adjusting the position of the stroke control lever 85 to a position effecting a shorter slide stroke. Likewise, the interlock positively prevents

60 making of an adjustment to the slide actuator that will increase the effective stroke of the slide, without first resetting the micrometer stop to a retracted position adequate for a lengthened slide stroke. In making the respective adjustments due allowance is preferably made to insure

65 a yielding of the slide blocks 35 and 36, for the reason previously explained, and the total yield there provided is, for reasons of safety, at least as great as the increment of change produced on shifting of the micrometer abutment from one whole unit division to the next.

In the device disclosed in Figs. 5 and 6 wherein the adjustment in the length of stroke of the follower is made to occur inside of a circle the adjusting lever, and interlock, and their connections, when such are employed in a given embodi-

ment of this movement, are arranged to suit the particular conditions, as will be understood, and in the interests of clarity, they have not been illustrated in their entirety in Figs. 5 and 6.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A filling machine of the volumetric displacement type combining a measuring cylinder and a cooperating piston reciprocable therein, piston reciprocating means comprising a rotatable and oscillatable cam member, means operatively connected to said cam to oscillate same, a follower member normally engaging said cam and adapted to be actuated thereby along a relatively fixed path during the oscillatory movement of the cam imparted by said means, yieldable connections between said follower member and said piston operative normally to transmit the motions of the former to the latter, means for moving said cam angularly relative to the path of movement of said follower member to effect a variation in the stroke thereof, and micrometer means for limiting the movement of said piston to a distance less than the normal stroke of said follower imparted by said cam in any of its angularly moved positions.

2. The combination set forth in claim 1 including means interlocking said micrometer means for limiting the movement of said piston with said means for moving said cam angularly to insure against incompatible adjustments of the said two means.

3. Dispensing apparatus of the character described combining a reciprocable measuring piston, means for actuating said piston comprising a rotatable and oscillatable cam member, a follower member normally engaged by said cam and movable thereby substantially radially of the axis of rotation of the cam member, means connected with the cam member for oscillating same, additional means operatively connected with the cam member for adjusting the cam angularly in a direction normal and relative to the path of movement of the follower member thereby to vary the resulting stroke of said follower, and an operative connection between said follower member and the said piston for transmitting the motion imparted to the follower to said piston.

4. The combination set forth in claim 3 including means independent of said piston actuating means operative positively to stop the travel of the said piston at a point short of the normal stroke of said follower member.

5. A filling machine of the character described having in combination a reciprocable measuring piston, means for reciprocating said piston in one direction comprising a shiftable and oscillatable lever, means connected with said lever for oscillating same, a follower member normally engaged by said lever and movable thereby, means connected with the said lever for shifting the lever bodily laterally in a direction normal and relative

to the path of movement of the follower member thereby to vary the resulting stroke of said follower, an operative connection between said follower member and the said piston for yieldingly transmitting the motion imparted to the follower to said piston, adjustable means effective upon said piston for stopping the travel thereof at a selected point independently of the normal stroke of said follower member, and means interlocking said lever shifting means and said piston stopping means to insure compatibility in their adjustment.

6. The combination set forth in claim 5 in which said follower member has an abutting engagement with said lever, and means operative independently of said lever for moving said piston in the opposite direction.

7. Actuating means for a follower roll comprising a pivoted lever provided with a circular track portion engageable by the follower roll, means connected to the lever for oscillating same about its pivot from an inner position wherein the track portion forms a portion of a cylinder to a position outwardly therefrom, and adjustment means to vary the location of the pivot of said lever along a line describing a circle, which circle is coaxial with said cylinder thereby to vary the outer limit of the follower movement.

8. The combination set forth in claim 7 in which the center of said follower roll is on the pitch circle of said cam track when the lever and its cam track are in said inner position.

9. A variable throw actuator for a cam follower comprising a rotatable support, a lever pivoted to said support, said lever having an arcuately formed follower-engaging surface thereon, means to oscillate said lever from an extreme position wherein the follower engaging surface constitutes a segment of a cylinder to another extreme position entirely to one side thereof, and means to adjust said support about the axis of said cylinder when so constituted and positioned and relative to the path of follower movement thereby to effect a change in the length of stroke of the follower.

10. The combination set forth in claim 9 wherein the angular movement of said support from zero stroke position to maximum stroke position is approximately 60°.

11. A variable throw actuator for a cam follower comprising a rotatable support, a lever pivoted to said support, said lever having an arcuately formed cam follower engaging surface thereon, means to oscillate said lever from an extreme position wherein the follower engaging surface constitutes a segment of a cylinder to another extreme position radially inwardly therefrom, means to rotate said support about an axis coincident with the axis of said cylinder whereby to shift the pivot of said lever relative to the line of contact made by the follower therewith.

12. Means to actuate a follower roll comprising a pivotally mounted lever provided with an arcuately shaped track portion engageable by the follower roll, means including a rotatable member operative on the lever for actuating the lever from one extreme position wherein the arcuately shaped track portion constitutes a part of a circle concentric with the axis of said rotary member to an opposite extreme position, a support for the pivot of said lever, said support being constructed for angular movement about an axis coincident with the axis of said rotary member and with the axis of the arc of said track when the latter is in concentric relation with the axis of said rotary

member, and means operative to shift the said support and said pivoted lever relative to the path of follower movement thereby to effect a change in but one of the extremes of follower movement.

FRANK J. COZZOLI.
